UNITED STATES PATENT OFFICE.

EVERETT W. BIGELOW, OF BOSTON, MASSACHUSETTS.

CORSET.

SPECIFICATION forming part of Letters Patent No. 228,725, dated June 15, 1880.

Application filed April 1, 1880. (No model.)

To all whom it may concern:

Be it known that I, EVERETT W. BIGELOW, of Boston, in the county of Suffolk and State of Massachusetts, have invented a new and 5 useful Improvement in Corsets; and I do hereby declare the same to be described in the following specification and represented in the accompanying drawings, of which—

Figure 1 is a front view, Fig. 2 a transverse section, and Fig. 3 a rear view, of the front portions of a duplex busk-corset having my invention. Figs. 4 and 5 are front views of the lapping portions of the duplex busk. Fig. 6 is a transverse section of the overlapping or 10 button-hole portion of the busk, Fig. 7 being a front view, and Fig. 8 an edge view, of one of the intermediate or connecting pieces thereof. In Letters Patent No. 215,560, dated May 20, 1879, and granted to me, I claim the under- 15 lapped portion, steel, or busk, provided with buttons, in combination with the overlapping or other portion provided with button-holes, arranged next alongside of the busk or busk-pocket of such portion, whereby by so arranging the button-holes the strain on the buttons while the corset is in wear is borne mainly, if not entirely, by the outer busk and the cloth saved from being torn away by the shanks or fastenings of the buttons.

30 In carrying out my present improvement I construct the overlapping portion of the duplex busk with two parallel steel or busk pockets, arranged close together, and having steels within them and button-holes formed between them, in order that the buttons projecting from the underlapping portion may be supported by either or both the steels in a manner to prevent such buttons from wearing or tearing away the button-holes while the corset 35 may be in use. Furthermore, in making the overlapping portion I combine its two busk-pocket pieces with intermediate connection-pieces arranged with and sewed to the pocket-pieces, as hereinafter described, so as to form 40 button-holes between the several connection-pieces and also between the pocket-pieces.

In the aforesaid drawings, A is the underlapping, and B the overlapping, portion of the duplex busk. The portion A has one pocket, 45 a, in it for the reception of a single steel, b, provided with a range of studs or buttons, c, ex-

tending from it in manner as represented. The overlapping portion B has two pockets, d d, arranged in it parallel to each other and a distance apart a little greater than the width of each of the button-holes f, the said button-holes being arranged and formed between the two pockets, so as to cause the steels thereof, after being inserted in them, to aid in preventing the buttons from straining or tearing out 60 the button-holes, not only when the two parts are buttoned together and the corset may be in wear, but during the process of disconnecting the said parts or unbuttoning one from the other.

65 In constructing the overlapping portion of the duplex busk I compose it of the two busk-pocket portions g h and a series of intermediate pieces, i i, the latter being arranged at short distances apart—that is, apart at distances corresponding to the lengths of the button-holes. These intermediate pieces extend into the pocket-pieces and are stitched or sewed thereto. I usually form each intermediate piece of a strip of cloth, of suitable length, sewed together at 70 its two ends; and folded at its middle, and I compose the pocket-piece h of a single strip of cloth, of suitable width, folded lengthwise along its middle and at its two opposite edges. The other pocket-piece may be made similar 75 to its fellow, or of two pieces of cloth laid one upon the other and turned in at those edges next to the fellow pocket-piece. In this way I am enabled to make a pair of steel-receiving pockets with button-holes between them without the necessity of working or sewing the edges of the button-holes in the manner as usually practiced when button-holes are made in cloth.

80 I am aware that it is not new to provide one of the buttoning portions of a corset with steel-receiving independent pockets having a web extending from one to the other, and provided with a series of metallic eyelets to engage with studs projecting from a steel in a pocket of 85 another buttoning portion of said corset.

85 With my invention the metallic eyelets are dispensed with, and in their place flexible button-holes are formed in the space or web of cloth between the two pockets and their studs. 90 In this way the strain of the studs on the button-holes is borne by one of the steels, and the

button-hole is thereby saved from being torn out by its button, the flexibility of the button-hole admitting of the steel to take the bearing of the stud, which is not the case when metallic eyelets are employed, such eyelets being very liable to be pulled out of the cloth or get out of place while the corset may be in use. One object of my invention is to avoid the use of such eyelets and in their place employ a flexible button-hole, and to so support it that it cannot readily be torn or injured either in the process of buttoning or unbuttoning the corset or while it may be in wear.

I claim—

In a duplex busk-corset in which the under-lapped portion is provided with a steel and buttons or studs projecting therefrom to connect such portion with the overlapping portion, having button-holes arranged between two steel-pockets and their steels, as described, the combination of the intermediate connection-pieces with the two busk-pocket pieces to form between them button-holes, as explained.

EVERETT W. BIGELOW.
